(57) **CLAIM**

The ornamental design for a monitor arm link, as shown and described.

DESCRIPTION

FIG. 1 is a bottom plan view of a monitor arm link showing the new design;

FIG. 2 is a front elevation view thereof;

FIG. 3 is a top plan view thereof;

FIG. 4 is a right side elevation view thereof;

FIG. 5 is a rear elevation view thereof;

FIG. 6 is a left side elevation view thereof;

FIG. 7 is a perspective view thereof;

FIG. 8 is a perspective view of the monitor arm link of FIG. 1 shown in an environment; and,

FIG. 9 is a perspective view showing two of the monitor arm links of FIG. 1 in another environment.

The broken lines in FIG. 1 depict portions of the monitor arm link that form no part of the claimed design.

1 Claim, 9 Drawing Sheets
